KNOCK-DOWN CABINET CONSTRUCTION
Myron E. Ullman, Jr., Canfield, Ohio, assignor to Mullins Manufacturing Corporation, Warren, Ohio, a corporation of OhioFiled July 5, 1962, Ser. No. 207,639
5 Claims. (Cl. 312—263)

This invention relates to a sheet metal cabinet construction and particularly to a new and novel method of assembling prefabricated and prefinished panels to form a rigid cabinet body structure which can be assembled economically at the point of use.

It is well known that so called knock-down cabinet constructions are economical from the standpoint of packaging, storage, and shipment because of savings in space. Knock-down construction also permits complete surface coverage of individual component parts with enamel finishes, which is impossible when applying a finish to a factory assembled and welded structure.

One of the principal objects of this invention is to provide simple locking means between adjoining prefinished panel members with universal application to an entire line of kitchen cabinetry including wall, linen, broom, utility, oven, base and undersink cabinet body structures. Field assembly can be carried out with a minimum of separate fastener means and tools to attain a rigid structure.

Another object of this invention is to provide interlocking means between main cabinet wall members and interior article supporting members to give strength and rigidity to the assembled cabinet body structure.

Another object of this invention is to provide a novel hinge bracket for interlocking vertical front panel members to horizontal front panel members for strength and rigidity of the assembled cabinet body structure.

Another object is to provide hinge brackets for a knock-down cabinet body structure for mounting cabinet doors in accordance with United States Patent No. 2,835,359.

Other objects will become apparent from the following description of the accompanying drawings, in which—

FIGURE 1 is a perspective view of an assembled wall cabinet body structure, shown with door panels removed for purposes of clarity.

FIGURE 2 is a perspective exploded view of a cabinet body structure.

FIGURE 3 is a section of a lanced hook along line 3—3 of FIGURE 2.

FIGURE 4 is a section of clearance holes in back panel shown along line 4—4 of FIGURE 2.

FIGURE 5 is a section of a lanced hook along line 5—5 in rear flange of end panel of FIGURE 2.

FIGURE 6 is an enlarged fragmentary sectional view along offset vertical planes indicated by lines 6—6 of FIGURE 1, showing the inter-relationship of basic components.

FIGURE 7 is a fragmentary top view of a front corner showing the relationship of hinge bracket, end panel and top panel.

FIGURE 8 is a fragmentary front view of the same upper front corner showing relationship of hinge bracket, end panel and top panel.

FIGURE 9 is a sectional view along line 9—9 of FIGURE 8 showing hinge and end panel locating detents or embosses.

FIGURE 10 is a front upper center fragmentary view showing the relationship of hinge brackets, top panel and a vertical mullion.

FIGURE 11 is a sectional view taken along line 11—11

2

of FIGURE 10 showing the interlocking relationship of hinge brackets, top panel and mullion.

FIGURE 12 is a perspective view of one of a pair of hinge brackets required for mounting each door.

5 FIGURE 13 is a sectional view showing the relationship of the rear center support for a long shelf panel and the lanced hook of FIGURE 3 in the back panel member.

FIGURE 14 is a partial sectional view along line 10 14—14 of FIGURE 8 showing the front mullion and flanges of an end panel.

FIGURE 15 is a perspective view of a composite base cabinet body structure upon which a work top, sink or other cabinet body structure may be placed, and which 15 shows one possible assembly of prefinished elements using different height door closures, drawer support guides, shelves, front and back mullions and a strike channel.

FIGURE 16 is an enlarged fragmentary view along the plane indicated by lines 16—16 in FIG. 15.

20 FIGURE 17 is a sectional view taken along lines 17—17 of FIGURE 21 of drawer guide rear tab in locked position with a vertical back mullion.

FIGURE 18 is a sectional view taken along line 25 18—18 of FIGURE 21 showing interlock of rear drawer guide tab in locked position with rear vertical flange of right hand end panel.

FIGURE 19 is a sectional view taken along line 30 19—19 of FIGURE 16 showing interlock of drawer guide front tab with notch in inturned flange of front mullion of right hand end panel.

FIGURE 20 is a sectional view taken along line 35 20—20 of FIGURE 16 showing hinge bracket assembly to right hand end panel to secure horizontal strike channel interlocked in notch of inturned flange of end panel front mullion.

FIGURE 21 is an enlarged fragmentary section taken 40 along the partial plane indicated by lines 21—21 of FIGURE 15 showing drawer and shelf supporting means in back mullions, rear flange of an end panel, and the back panel member.

FIGURE 22 is a perspective fragmentary view of the lower front corner of a left hand end panel of a base cabinet body.

FIGURE 23 is a fragmentary sectional view showing a 45 kick plate hooked to the recessed vertical flange portion of left hand end panel shown in FIGURE 22.

FIGURE 24 is a perspective view of a vertical center mullion for wide base cabinet body structures having multiple compartments.

50 FIGURE 25 is a perspective view of a vertical rear mullion for supporting rear shelf flanges and rear drawer guide tabs.

FIGURE 26 is a perspective view of a left hand drawer guide of a pair of left and right hand guides for supporting sliding drawers.

The wall cabinet

FIG. 1 illustrates one of several possible embodiments of a wall cabinet structure contemplated by this invention. Basically, the body structure comprises the following panels: a top 50, ends 51 and 52, a back 53, a floor 54, and a bottom 55. In addition a shelf 56 is shown mounted within the body structure formed by the aforesaid panels.

65 Referring now to FIGS. 1, 2 and 6, top panel 50 has a depending front flange 80 terminating with an inturned flange 83, and a rear flange 80' terminating in hooked edge portion 82. As best shown in FIG. 2, portions of front flange 80 are provided with pairs of adjacent clearance holes 95 and 100 for purposes presently described.

Since end panels 51 and 52 are the opposite structural

counter part of each other, only the structural formation of panel 51 will be described in detail. As best shown in FIGS. 2, 6 and 14, end panel 51 has top and bottom flanges 70 and 71, front mullion 66 with inturned flanges 67 and 68, and a back flange 69.

Referring more particularly to FIG. 6, flanges 67 and 68 are notched at their upper and lower end portions to receive top panel 50 and floor and bottom 54 and 55. Flanges 67 and 68 are also notched as at 72 to receive and support the front edge of shelf 56. Back flange 69 is lanced, as shown in FIG. 5, to form hooks 73 for supporting rear flange 84' of shelf 56, and rear flange 87' of floor 54.

As illustrated in FIGS. 2 and 6, the upper portion of back panel 53 is provided with an angular offset 76, a vertical flat portion 77, and a top right angle flange 78 which terminates in a down turned flange 79. As a result flange 79 is received in and interlocks with hook-edge portion 82 of top 50 as shown in FIG. 6. Along the sides and adjacent the edges of the main vertical flat portion of back panel 53, rectangular holes 74 are provided to receive hooks 73 which project from flanges 69 of end panels 51 and 52. Additional lanced hooks 75 are provided in the center of the main vertical portion of panel 53 to provide center support to back flange 84' of shelf 56 and rear flange 87' of floor 54.

Bottom panel 55, as shown in FIGS. 2 and 6, has upturned end flanges 96 and 96', a rear upturned flange 91' and a front edge formation which has a front face portion 91, an inturned upper flange 94, and an inturned lower portion 92 which is spaced above the main flat panel area by a right angle offset portion 93. As illustrated in FIG. 2, front face 91 has one or more rectangular holes 97 to receive catches for door strikes not shown herein. Clearance holes 100 are provided in the ends of front face 91 for lower detents 98 in end panels 51 and 52, and bolt holes 95. Bottom 55 rests on bottom flanges 71 of end panels 51 and 52.

As shown in FIGS. 2 and 6, floor panel 54, which has downturned end flanges 88 and 88', and front and rear downturned flanges 87 and 87', rests on bottom 55 with front flange 87 supported on the ledge formed by portion 92, while end flanges 88 and 88' are supported on the floor panel end flanges 96 and 96' and the rear flange 87' is locked against back panel 53 by the lower hooks 73 in end panel rear flanges 69. Floor panel 54 is further securely held in position as a result of its front flange 87 resting in abutment with inturned flange 94 of bottom 55. Notches 90 in front flange 87 clear catches inserted in holes 97 of front face or mullion 91 of bottom 55. End notches 89 in flange 87 are for clearance of hinge bracket mounting means presently described.

FIGS. 8 and 9, which are front and side views respectively, of the upper left top corner of the wall cabinet, show how a hinge bracket 58 (FIG. 12) is located by inserting the rear projection of detent 60, provided on bracket 58, into receiving detent 98 which is formed in front mullion 66 of end panel 51, and by inserting a pan head bolt 61 through holes 63 in the hinge bracket and aligned holes 99 in end panel mullion 66 and 95 in mullion 80 of top panel 50. Hole 100 in mullion 80 of top panel 50 is large enough to clear detent 98 in end panel mullion 66. The offset 65, which is formed on hinge bracket 58 (FIG. 12), abuts on the surface of mullion 80 so as to take up the metal thickness of end panel mullion 66, which is in lapped abutment with the outer surface of mullion 80. When the nut is tightened on bolt 61, this corner becomes quite rigid against any movement of any of its parts.

In the event it is desired to have a wide cabinet with four doors, FIG. 1 shows the use of a center vertical mullion 57 and two additional pairs of hinge brackets 58 and 59. The mounting of the top pair of hinge brackets is shown in FIGS. 10 and 11. In this case the receiving detents 98 for hinge detents 60 are formed on the front

face of mullion 57 adjacent its upper and lower edges. Thus bolts 61 secure the hinge brackets to vertical mullion 57 and front mullion 80 of top panel 50. The bottom end of vertical mullion 57 is similarly attached to front mullion 91 of bottom panel 55 adding further rigidity to a wide cabinet body structure while supplying additional door mounting means.

It is understood that cabinet body structures may be assembled similarly whether one, two or more doors are required to serve as front closures. It is also understood that one or more shelves may be used and each made adjustable by providing additional notches 72 in end panel flanges 67 and 68 depending on the body height, and corresponding flanges of any center mullions required. Furthermore when additional or adjustable shelf locations are desired, additional appropriately positioned lanced hooks 73 and 75 in end panel flanges 69 and back panel 53, respectively, are made to suit.

The assembly of a cabinet body structure from the component panels and members herein described is relatively simple. The back panel 53 is placed on a flat surface, top panel 50 is hooked onto top flange 79 by its hook edge 82. Each of the end panels, 51 or 52, is positioned at the appropriate end of panel 50 so that the upper edge 25 of top panel 50 is under top flange 70 of the end panel, and hooks 73 are received in rectangular holes 74 of back panel 53. The upper front corners are then fastened by assembling hinge brackets 58 and 59 as above described and as shown in FIGS. 7 and 8. The bottom panel 55 is then positioned between the opposite end panels 51 and 52, so as to rest on flanges 71. The lower front hinge bracket is assembled as was the top bracket. Another pair of hinge brackets 58 and 59 are then secured to the lower front corners. If a single door cabinet is involved, 35 bolts 61 are used without the hinge brackets inserting them through upper and lower end panel holes 99, and top and bottom panel holes 95 of the unhinged upper and lower front corners. Floor panel may then be placed 40 on top of bottom panel 55 with its rear flange portion 87' engaged by hook 73 and its front flange 87 resting on portion 92 of panel 55. A shelf 56 may then be placed within the cabinet and supported in front notches 72 and rear hooks 73 of each end panel and also by upper hook 75 of back panel 53.

It will become apparent that when the floor panel 54 and one or more shelves 56 are in place, back panel 53 is firmly locked in position, since back flange 84' of the shelves 56 and back flange 87' of the floor panel 54 are between hooks 73 of the end panels and hooks 75 of the back panel member 53, thus holding back panel in place and adding strength and rigidity to the cabinet body structure.

The base cabinet

The basic principles of construction which are the subject matter of this invention and which were used to provide the wall cabinet assembly described above, may also be employed in the construction of a base cabinet. One embodiment, of the many arrangements which are possible, is shown in FIG. 15.

Any arrangement in a single base cabinet unit can be combined with one or more similar units so that only one pair of end panels will be required by using intermediate front and rear vertical mullions to separate the various storage compartments. A top channel frame and floor panel govern the overall length of the body structure.

The combination base cabinet structure shown in FIG. 15 has a set of end panels 151 and 152, a top channel frame 150 upon which is secured a separate worktop, sink, or range top, or combinations thereof, none of which are shown here since this invention deals only with the cabinet body structure. In addition, the cabinet structure has a partial back panel or panels 153, floor panel 154, kick plate 155, front mullion 157, rear mullions 158 and 159, a horizontal strike channel 160 and a pair of drawer support guides 161 and 162 (FIG. 21).

Since end panels 151 and 152 are opposite counterparts, a reference to the basic structural arrangement of either one will likewise pertain to the other. The top of end panels 151 and 152 have an inturned flange 101, and down turned flange 102 which hooks over the ends of top channel 150 as shown in FIG. 21 at 101' and 102' which are the corresponding flanges of end panel 152. The front flange 103 forms a vertical mullion having an inturned flange 104. Inturned flange 104 has a series of notches 105 and 106 spaced to determine the proper location and front support for drawer guides 161' and 162, shelves 156 and strike channels 160. Rear inturned flange 107 of end panel 151 has a series of lanced brackets 108 and lanced hooks 109, aligned with front flange notches 105 and 106, respectively. By these means drawer guides 161 (FIG. 26) and 162 are supported by inserting hook portion 126 into notch 105 and the wedge shaped flange into lance bracket 108. Shelf 156 is supported by inserting its front flange portion into notch 106 and by hooking its rear flange 135 over hook 109, as shown in FIG. 16.

The upper and lower portions of front mullion 103 have provisions for mounting a pair of hinge brackets 58 and 59 with detents and holes 98 and 99, respectively (FIG. 20), as described above in relation to the end panel front mullions and hinge brackets of wall cabinets.

The lower front corners of end panels 151 and 152 are cut out to provide toe clearance inasmuch as the end panels rest on the floor of the room in which they are installed. In FIG. 22, a partial perspective view of the lower front corner of end panel 151 shows the flanging 111, 112, 113 and 114 which define the toe clearance space. Bottom inturned flange 110 of end panel 151 rests on the floor of the installation area. Flanges 113 and 114 support the front corners of floor 154 of the cabinet body structure. Inturned flanges 111 and 112 are shown in partial section in FIG. 23 in relation to the interlocking of a kick plate 155. FIGS. 15 and 16 show end panel members 151 and 152 and a hooked bracket 130 which is spot welded to the back of kick plate 155 and which slides into hooked and locked relationship with flanges 111 and 112.

A front vertical mullion 157 is shown in FIG. 24 with top inturned flange 117 and downturned flange 118 which hooks over front channel member 136 (FIG. 15) of top frame 150. Bottom flange 119 supports the front center portion of floor 154. Detents 98 and holes 99 in the front face of mullion 157 are for mounting hinge brackets 58 and 59 previously described in relation to the wall cabinet body structure. Notches 105 and 106 in inturned side flanges 115 and 116 are aligned with and correspond to similarly identified notches in end panel flanges 104 and 104' of end panels 151 and 152, respectively.

The smaller notches 105 provide location and support for front lanced hooks 126 in drawer guides 161 (FIG. 26) and 162. FIG. 16 shows the interlock of drawer guide front hook 126' in notch 105 of end panel 152.

FIG. 15, 16 and 20 show the manner of supporting and locking strike channel 160 in large notches 106. The hook means 131 formed on the inturned flanges at the opposite ends of the front web portion of the channel 160, fit into notch 106 of flange 104', and over the unnotched portion of flange 115 of center mullion 157. Hinge bracket 59 (FIGS. 16 and 20) fits into detent 98 nearest to flange 115 of mullion 157 and bolt 61 secures strike channel 160 to the mullion using hole 63' of hinge bracket as shown in FIG. 12. Rectangular holes 97 in strike channel 160 are to receive strike catches, not shown. Shelf 156, as shown in FIG. 16, is similar to the shelving used in the previously described wall cabinet, and is supported at its front channel edge by notches 106 in mullion 157 and by hook 109 in end panel 152.

Floor 154 has the same exterior dimensions as top channel frame 150, and its front corner edges are supported by flanges 113 and 114 of end panel 151, and by

corresponding flanges 113' and 114' of end panel 152 as shown in FIG. 16. The center front section of floor 154 is supported by flange 119 of mullion 157 (FIGS. 15 and 24).

It is noted here that end panel flanges 104 and 104' and mullion 157 side flanges 115 and 116 are notched out at the top to clear top channel frame 150. Likewise the bottom portions of these flanges are notched to permit entrance of the front edge section of floor 154. The front edge faces of both top frame 150 and floor 154, have clearance holes 100 for receiving detents 98, and holes 95 to receive bolts 61 for the mounting of hinge brackets 58 and 59 to end panel members 151 and 152, as well as to vertical mullion 157. As shown in FIG. 16, kickplate 155 has an outward turned top flange 133 supporting floor panel 154, and inturned bottom flange 134 in the same plane as the bottom flanges 110 and 110' of end panels 151 and 152.

A pair of rear vertical mullions 58 and 59 are shown in position in FIG. 21. The right rear vertical mullion 159 is shown in perspective in FIG. 25 and has an angular cross section with a back leg 120 and a forward leg 121. Back leg 120 has a top inturned flange 122 and downturned flange 123 which hooks over the rear channel section 137 of top frame 150. Leg 121 is notched out at the top to clear top channel section 137 when flanges 122 and 123 of mullions 158 and 159 are hooked over it. Floor panel 154 is supported, in part, by having its rear flange portion 138 in resting engagement within notch 124, and also within the wide angled hook 125 formed in back leg 120 of mullions 158 and 159.

The back legs 120 of mullions 158 and 159 have a number of lanced hooks 109 and lanced brackets 108 corresponding in structure and position with hooks and brackets 35 in inturned back flanges 107 and 107' of end panels 151 and 152. A portion of lanced hooks 109 are aligned with front flange notches 106 for supporting shelves at different locations within the cabinet. Lanced brackets 108 are aligned with front flange notches 105 for locating and supporting drawer guides 161 and 162. Rear flange or tab 127 of drawer guide 161 has a reduced portion slightly tapered as at 128 which fits into lanced bracket 108 and notch 129 serves as a stop against the side of 40 108 lanced bracket as shown in FIG. 21. The positioning of guide 162 is shown similarly in FIG. 21.

Back panel 153 while of less height than the full height of the end panels, extends from the floor to a height about half the height of the end panels. Rectangular holes as at 74 in back panel 53 shown in FIG. 21 are over the lanced hooks 109 and lanced brackets 108. Either the back flanges of shelves and floors in lanced hooks 109, or the rear flange tab 127 of the drawer guides in brackets 108 lock the back panel to the inside of flanges 107 of the end panels and back leg 120 of rear vertical mullions 158 and 159 as shown in FIGS. 16 and 21.

Top frame 150 is rectangular and made up of channel sections 136 and 137 as shown in FIGS. 16 and 21. Gussets 132 are welded at each corner for stiffness. Front channel member 136 acts as a strike channel with rectangular holes 97 for strike catches not shown, and holes are provided at each end and intermediate as in floor section 154 for detent clearances and bolts 61 to secure hinge brackets 58 and 59 in place as required. The upper sections of FIG. 21 show in dotted lines a top supported drawer in sliding position in a pair of drawer guides 161 and 162. The assembly of a base cabinet body structure is similar to the procedure followed in assembling the wall cabinet structure.

It will be understood that two or more compartments may be provided in a single base cabinet body structure and any combination of shelves and drawers may be used to provide storage capacity and shelf area required. The hinge brackets secure the front corners, and the back panels are held in place by shelves, floors and drawer slides, all serving to provide a rigid, sturdy structure

easily assembled with a minimum of separate fasteners.

This construction applies equally well to cabinets having greater height than width such as broom, linen, utility and built-in oven cabinets. Such cabinets usually require more than one pair of doors, one pair being mounted above the other. These additional doors require a horizontal strike channel located intermediate the top and bottom panels of the cabinet body, similar to that shown above for base cabinets, but are adapted to receive two sets of strike catches and two pairs of hinge brackets. The additional mounted hinge brackets add greatly to the rigidity of these tall narrow cabinet structures which also have full height locked in back panels for additional strength.

These tall cabinets are readily adapted for installations of built-in ovens located at convenient working heights, with doors mounted above and below the oven. Shelves, drawer guides and oven supporting means are readily installed using the notches located in end panel flanges, and the combination of mounted hinge brackets, horizontal front mullions, and locked in back wall panel members, assure the strength and rigidity required for such an installation.

Having thus described my invention, what I now claim is:

1. In a cabinet body structure assembled from interlocking prefinished panel members, the combination including a front corner of the body structure formed by adjoining vertical and horizontal front mullions of vertical and horizontal panel members, a hinge bracket having a detent embossed therein, a detent formed in the front mullion of the vertical panel member to receive said hinge bracket detent emboss, clearance for said detent in the front mullion of the horizontal panel member, aligned holes in the hinge bracket and adjoining vertical and horizontal front mullions for inserting and securing a single fastener means to form a rigid corner structure and hinge bracket mounting.

2. In a cabinet body structure assembled from interlocking prefinished panel members, the combination of rear vertical flanges of vertical panel members, a back panel member, shelf panels and other article supporting means within the cabinet body, wherein the vertical rear flanges of vertical panel members have lanced hooks and brackets therein for supporting the rear downturned flanges of shelves or flanges of other article supporting means, clearance holes along the vertical edges of said back panel member for the lanced hooks and brackets of vertical rear flanges of vertical panel members, the back

panel member being placed against the rear flanges of the vertical panel members so that the lanced hooks and brackets protrude inwardly through the clearance holes so that the rear down-turned shelf flanges and flanges of other internal article supporting means are supported by the lanced hooks and brackets and at the same time hold the back panel member securely in relation to adjoining flanges of vertical panel members.

3. In a cabinet body structure in accordance with claim 1, in which at least three front corners formed by vertical end panels and horizontal top and bottom body structure members are secured against movement by interfitting hinge brackets.

4. In a cabinet body structure in accordance with claim 3, comprising in addition a horizontal strike channel member extending parallel to said horizontal front mullion and at least two interfitting hinge brackets being secured to said horizontal strike channel member.

5. In a cabinet body structure assembled from interlocking prefinished components consisting of top, bottom, end, back and front components, wherein front mullion portions of top, bottom and end components are secured to each other and to any separate front mullion components by single fasteners in each hinge bracket attached to a pair of vertical and horizontal adjoining front mullion surfaces, said hinge bracket being located on vertical mullion surfaces by projections and depressions of matching detents embossed in said hinge bracket and in said front vertical mullion surfaces spaced relative to said single fasteners to prevent twisting of said hinge brackets relative to said front mullion surfaces.
